UNITED STATES PATENT OFFICE

97,123

DESIGN FOR A COMBINED DISPLAY STAND AND CONTAINER THEREFOR

John F. Daniell, New York, N. Y.

Application September 21, 1934, Serial No. 53,353

Term of patent 3½ years

To all whom it may concern:

Be it known that I, John F. Daniell, a citizen of the United States, residing at New York, in the county of New York and State of New York, have invented a new, original, and ornamental Design for a Combined Display Stand and Containers Therefor, of which the following is a specification, reference being had to the accompanying drawing, forming part thereof.

In the drawing:

Fig. 1 is a front elevational view of a combined display stand and containers therefor, showing my new design;

Fig. 2 is a side elevational view; and

Fig. 3 is a plan view.

I claim:

The ornamental design for a combined display stand and containers therefor, as shown.

JOHN F. DANIELL.
